CLAIM

The ornamental design for an attachable document case
for facsimile transceivers or the like, as shown and de-
scribed.

DESCRIPTION

FIG. 1 is a front elevational view of an attachable docu-
ment case for facsimile transceivers or the like showing
my new design;

FIG. 2 is a rear elevational view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a right front perspective view thereof, the
broken-line showing of a facsimile transceiver is envi-
ronmental only and forms no part of the claimed design.
